UNITED STATES PATENT OFFICE

2,400,644

MILITARY CHESS GAME

Benjamin Hoffman, Brooklyn, N. Y.

Application January 29, 1944, Serial No. 520,154

3 Claims. (Cl. 273—131)

This invention relates to new and useful improvements in a military chess game.

More specifically, the invention proposes the construction of a military chess game characterized by a board formed with twelve squares along one side and eight along the other in a manner so that players may place their pieces along the length of the board on opposite sides thereof.

A further object of the invention proposes the provision of a folding smoke screen adapted to be extended along the center of the board in a manner to separate the board and permit the players to secretly position their pieces in the starting squares so that when the smoke screen is removed to start the game, the set up of each player's pieces will be revealed, adding the element of surprise to the game and thus increasing the interest thereof.

A further object of the invention proposes the provision of a military chess game in which actual military moves of a battlefield are accurately simulated and in which the addition of the smoke screen permits the element of surprise to be carried out.

Still another object of the invention proposes the provision of a removable and foldable overcast section which is adapted to be mounted upon the smoke screen to extend in opposite directions therefrom over the top of the board to further eliminate the possibility of the players observing the manner in which his opponent is setting up his pieces.

Still another object of the invention proposes the provision of a game in which each person is provided with eighteen pieces consisting of eight infantrymen, two light tanks, two heavy tanks, two airplanes, two anti-aircraft guns, and two heavy artillery pieces, with each of the pieces having specific moves with relation to each other and the ability to knock each other out of the game to permit a winner to be determined when one of the opposing players has managed to move one of his pieces the complete width of the board and to the rear line of defense of his opponent.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a view illustrating each of the different types of pieces used in playing the game.

Fig. 2 is a perspective view of the board used 55

for playing the game with the pieces set in a proper starting position on opposite sides of the board.

Fig. 3 is a partial view of the board illustrating the manner in which the infantry pieces are moved.

Fig. 4 is a partial view of the board illustrating the manner in which the light tank pieces may be moved.

Fig. 5 is a portion of the board illustrating the manner in which the heavy tank pieces may be moved.

Fig. 6 is a portion of the board illustrating the manner in which the airplane pieces may be moved.

Fig. 7 is a partial view of the board illustrating the manner in which the anti-aircraft gun pieces may be moved.

Fig. 8 is a portion of the board illustrating the manner in which the heavy artillery pieces may be moved.

Fig. 9 is a view of the board illustrating the manner in which the winner is determined.

Fig. 10 is a side elevational view of the board 25 constructed in accordance with a modification of the invention.

Fig. 11 is a plan view of Fig. 10.

Fig. 12 is a partial vertical sectional view taken on the line 12—12 of Fig. 11.

30 The military chess game, according to this invention, is adapted to be played upon a checker board 10 having its surface divided into a plurality of squares 11. The board 10 is provided with twelve squares along one side and eight squares along its adjacent side. This construction imparts a rectangular shape to the board 10. A group of differently colored military pieces 12 are adapted to be placed on the board in certain allowable positions by the players. The pieces 12 are differently colored to be distinguishable by the players, and at the start of the game, as shown in Fig. 2, the pieces may be arranged in any desired positions in the first two rows on opposite sides of the length of the board 10. The pieces 12 are preferably eighteen in number for each side and consist of eight infantry men 12^a, two anti-aircraft guns 12^b, two light tanks 12^c, two heavy tanks 12^d, two airplanes 12^e, and two heavy artillery pieces 12^f.

45 The board 10 is also provided with a foldable smoke screen 13. This foldable smoke screen 13 is adapted to be extended along the center of the length of the board, permitting each of the players to position his pieces 12 as desired upon his side of the board independently and secretly

of the opposing player. When the game is about to start the smoke screen 13 is removed from the center of the board revealing the position of the pieces to each player. The use of the smoke screen imparts the element of surprise to the game, increasing the interest of the game in that each player attempts to so position his pieces as to be in a superior position with relation to the set up of the pieces of his opponent.

In playing the game each of the pieces 12 is adapted to be moved in a specific direction and a given number of squares upon the face of the board 10. The details of the manner in which the pieces are adapted to be moved will be individually described.

The infantry pieces 12^a and the manner in which they are adapted to be moved on the board 10 is illustrated in Fig. 3. The infantry pieces 12^a are similar to the pawns in a conventional chess game and is the only piece whose move is similar to the pieces in a chess game. On its initial move from its starting position the infantry piece 12^a may move at option one or two squares in any direction, and after that is limited to movements of one square at a time. The infantry piece 12^a may only capture another piece when moved in a diagonal direction, as indicated on Fig. 3 by the position of the letters C. In capturing a piece the infantry piece 12^a moves into the square occupied by the captured piece and may only capture one piece at a time, and the said piece must be immediately adjacent thereto.

The manner in which the light tanks 12^c are moved on the board 10 is indicated in Fig. 4. The light tank may move one square at a time forwards, backward, or diagonally from the square it occupies. The light tank 12^c may not move sidewise and captures an opposing piece by moving into the square occupied by the piece when immediately adjacent the light tank.

Movements of the heavy tank 12^d on the face of the board 10 is indicated in Fig. 5. The heavy tanks 12^d, like the light tanks 12^c, may move only forwards, backwards and diagonally from the space occupied. Movements of the heavy tank differ from the light tank in that the heavy tank is capable of moving one or two squares in the given directions on any one play and also captures an opposing piece by moving into the square occupied by the piece.

Movements of the airplane 12^e are illustrated in Fig. 6. The airplane 12^e bears a slight resemblance to the knight in a conventional chess game in that it can jump or fly over other pieces on the board. The airplane pieces 12^e have the greatest mobility on the board and may move forward, backwards, sidewise or diagonally in a straight line from the space it occupies and may land in any square not occupied by another piece. The airplane 12^e is limited in its ability to capture another piece in that it may capture only those opposing pieces immediately adjacent the square it occupies. It may not fly over a piece in order to capture an opposing piece on the opposite side of the piece over which it passed.

The movements of the anti-aircraft gun 12^b are illustrated in Fig. 7. The anti-aircraft gun pieces 12^b are capable of moving forwards, backward, sideways, and diagonally from the space occupied, but the movement may not exceed more than five squares on any given play. It may capture an airplane piece 12^e of the opponent only if the airplane is in the line of movement of the anti-aircraft gun, and captures the airplane by moving into the space occupied by the

opposer's airplane piece. It may not capture any other piece on the board. In the event all of the airplane pieces of the opposing side have been captured, the anti-aircraft gun then assumes the power of an infantryman and moves and captures opposing pieces in the manner previously outlined for infantry pieces.

Movements of the heavy artillery pieces 12^b are shown in Fig. 8. As in actual warfare, the movements of the heavy artillery pieces are comparatively limited, but each has a tremendous striking power. These pieces may move forwards, backwards, sideways and diagonally one square at a time. In capturing pieces of the opposing side, the heavy artillery piece differs from the capturing powers of the other pieces in that it does not move into the box occupied by the opposing piece. It has the power to permit the side possessing the piece to remove all pieces of the opposer which stand in its line of fire and remains in its own square. However, the removal of an opposer's piece without moving the artillery constitutes a move. The fire power of the heavy artillery piece is limited to three squares in a straight line from the square it occupies and is also capable of firing over pieces located in squares between the square it occupies and the square occupied by the opposer's piece.

The heavy artillery pieces 12^b may not capture airplane pieces 12^e.

On each of Figs. 3 to 8 which indicate the manner of moving the various pieces, the X's appearing in the squares indicate the directions in which the pieces may be moved, and the C's in the squares indicate the capturing ability and the direction in which the pieces may be moved to capture an opposer's piece. The game is continued until one of the players is capable of moving one's piece completely across the board and into the line of last defense of his opponent, as illustrated in Fig. 9. The last line of defense for each of the players is the first line of twelve squares immediately adjacent the edge of the board.

In the modification of the invention shown in Figs. 10, 11 and 12, the smoke screen 13 is provided with a removable and foldable overcast section 20. The removable and foldable overcast section 20 is adapted to be supported upon the top edge of the smoke screen 13 and to extend in opposite directions therefrom over the top of the board, as shown in Figs. 10 and 11. The top edge of the smoke screen 13 is provided with a plurality of upwardly extended pins 21 which are adapted to be releasably engaged with bayonet slots 22 formed in the section 20 at its fold line.

Movement of the overcast section 20 relative to the smoke screen 13 aligns the heads of the pins with the enlarged portions of the slots 22, permitting the overcast section 20 to be lifted out of its engaged position with the smoke screen 13 to be folded, permitting it to be stored in a minimum of space when not in use. The provision of the overcast section 20 eliminates the possibility of the players peering over the top edge of the smoke screen 13 to observe the manner in which the opposer is placing his pieces upon the board.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right 75 is reserved to all changes and modifications com-

ing within the scope of the invention as defined in the appended claims.

Having thus described my invention, what I claim as new, and desire to secure by United States Letters Patent is:

1. In combination with a game board, a removable screen engaging across said board, said screen including a removable section positioned on the upper edge of said screen and extending in opposite directions therefrom, and means removably mounting said section in position on said screen.

2. In combination with a game board, a removable screen engaging across said board, said screen including a removable section positioned on the upper edge of said screen and extending in opposite directions therefrom, and means removably mounting said section in position on said screen, said means comprising upwardly extend-

ing spaced pins mounted on the top edge of said screen and releasably engaging complementary bayonet slots formed in said section.

5 3. In combination with a game board, a removable screen engaging across said board, said screen including a removable section positioned on the upper edge of said screen and extending in opposite directions therefrom, and means removably mounting said section in position on said screen, said means comprising upwardly extending spaced pins mounted on the top edge of said screen and releasably engaging complementary bayonet slots formed in said section, said screen having portions extending to opposite sides of a line passing through said pins whereby said section is supported in a substantially horizontal position.

BENJAMIN HOFFMAN.
